2,361,829

FOLLOWER FOR FILE DRAWERS

Fred C. Drebes, Chicago, Ill., assignor to Boynton & Company, Chicago, Ill., a corporation of Illinois

Application December 21, 1942, Serial No. 469,645

4 Claims. (Cl. 129—29)

This invention relates to followers for filing drawers and has as its principal object the provision of a drawer follower which will be simple in construction, economical in manufacture and highly efficient in use.

An object of this invention is to provide a follower with a finger-operated lever for clamping the follower in a fixed position in a filing drawer.

Another object of this invention is to provide a follower with a cam lever which will coact with guiding means in the drawer for wedging the follower in desired positions.

A further object of my invention is to provide an eccentric camming lever, the pivot mounting of which cooperates with follower guiding means in a drawer to bind the follower in various positions of adjustment.

Still another object of this invention is to provide a follower for a filing drawer and having movable camming levers held in assembly by reason of their relationship to the drawer.

Other objects will appear more fully hereinafter.

The invention consists in the novel combination and arrangement of parts to be hereinafter described and claimed.

The invention will be best understood by reference to the accompanying drawings showing my new construction for a follower and in which:

Fig. 1 is a perspective view of a filing drawer with my new follower associated therewith;

Fig. 2 is a fragmentary vertical sectional detail view through the follower as seen along line 2—2 in Fig. 1;

Fig. 3 is a cross sectional detail through the filing drawer showing my follower in vertical sectional detail as seen from line 3—3 in Fig. 2;

Fig. 4 is a fragmentary perspective view of an end wall of my new follower;

Fig. 5 is a perspective view of a modification of my follower structure; and

Fig. 6 is a vertical sectional detail similar to that of Fig. 2 but illustrating my modification shown in Fig. 5.

Referring to the drawings, my new follower is shown associated with the usual drawer 10 having parallel sides 11 and 12 and a front and back wall, 13 and 14, respectively, together with a bottom wall 15 for supporting articles in the drawer. The side walls 11 and 12 are provided with guiding means for the follower through the medium of grooves 16 rabbeted in the inside face of the drawer sides in a plane parallel to and spaced from the bottom wall 15.

The follower is generally indicated by the ref-

erence numeral 17 and consists in the main of a base member 18 providing a vertical bearing surface 19 disposed to bear against the rearmost sheet of a plurality of sheets 20 disposed in the drawer 10. The follower has a base surface 21 arranged for movement over the bottom wall of the drawer toward and away from the articles 20 to be bound in the drawer.

The follower is completed by the provision of a novel locking means for holding the follower in any desired position of adjustment. The locking means comprises a pair of levers 22 arranged for pivotal movement on the ends of the base member 18. The means for pivotally mounting each lever 22 on the base member is a dowel pin 23 having a head 24 which projects beyond the outside face of the lever 22.

The heads 24 perform the two-fold function of retaining the levers 22 on the base member and to provide trunnion members which project into the guiding means for slidable movement therewith. The levers 22 conform in contour to the base member 18 with the exception of their lower extremity 25 which is circular in shape and has a bearing opening 26 formed eccentrically with respect to the outer curved edge 27. In this manner the edge 27 is disposed at a shorter radius from the axis of the bearing opening 26 on that side of the lever adjacent the rear of the base member 18 when the lever is in normal position as seen in Figs. 1 and 2 than is that edge of the lever which is aligned with a long axis struck through the lever 22. The segmental arc between the foregoing two points on the edge 27 is graduated in radius thereby creating a camming action when the lever is rotated between its two extreme positions.

The levers 22 are slightly shorter than the full height of the follower 17 so that when the levers 22 are disposed in released condition (lowest position in Fig. 2) the follower may be reasonably close to the rear wall 14 of the drawer. The upper and outside corners of the follower 17 are cut away to a level to permit a slight portion of the lever to extend thereabove, thus providing finger tabs 28 whereby a person can urge the lever 22 out of normal condition (as illustrated in dotted lines in Fig. 1).

The dowel pins 23 being freely mounted in the sockets 29 formed in the ends of the base member 18 are free to slide in and out with respect thereto. By reason of this characteristic the follower is easily installed into the drawer 10 which installation is accomplished by placing the base member at an oblique angle in the drawer,

the lever and pins being assembled thereon, and turning the base member to a position transversely of the drawer, the dowel pins giving sufficiently to permit the levers and base member to spring into slidable relation with respect to the guiding means and drawer.

With the follower 17 thus positioned it may be pressed tightly against the sheets 20 and thereafter the levers rotated from a horizontal condition to a vertical condition, thereby rotating the graduated edge 27 on the lever 22 into camming relation with the bottom 15 of the drawer. The camming action of the lever 22 urges the dowel pins 23 upwardly causing the head portions 24 thereof to bear tightly against the upper walls of the grooves 16, thereby wedging the entire follower 17 in a fixed position against the sheets 20 to hold the latter in uniform vertical condition.

The two levers 22 may be joined by a tie rod 30 as shown in the modification illustrated in Figs. 5 and 6. In this form of my invention all of the essential parts of the form shown in Figs. 1 to 4 inclusive are present and are indicated by like reference characters, the only variation being found in the elimination of the finger tabs 28 at the free ends of the levers 22. In lieu of the tabs 28 the free ends of the levers 22 have openings 31 formed therein with such openings in axial alignment with each other and in these openings are disposed the respective ends of the tie rod or bar 30. The rear face of the base member 18 is rabbeted as at 32 to permit the levers with tie rod attached to assume a vertical or camming position. The upper edge 36 of the base member 18 is cut away at its mid section as at 37 to expose the medial portion of the tie rod 30 whereby a person may by a single hand operation actuate both levers 22 simultaneously.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In a follower for a filing drawer in which the drawer is provided with guiding means, said follower comprising a base member disposed transversely of the drawer on the bottom wall thereof, lever means arranged at the ends of

said base member, and means pivotally mounting said lever means on said base member, said last named means comprising a headed pin at each end of the base member, having the head portion thereof arranged to engage the corresponding guiding means and adapted to coact with said lever means to wedge said follower in a desired position between the guiding means and the bottom of the drawer.

2. In a follower for a filing drawer in which the drawer is provided with guiding means, said follower comprising a base member disposed transversely of the drawer on the bottom wall thereof, lever means arranged at the ends of said base member and having a camming surface arranged for graduated engagement with the bottom wall of the drawer, and means pivotally mounting said lever means on said base member, said last named means comprising a headed pin at each end of the base member having the head portion thereof arranged to engage the corresponding guiding means and adapted to coact with said lever means to wedge said follower in a desired position between the guiding means and the bottom of the drawer.

3. In a follower for a filing drawer having guiding channels formed in the side walls thereof and parallel to the bottom wall thereof, said follower comprising a body portion providing a vertical face adapted to bear against pieces disposed in the drawer and providing a base surface slidable over the bottom wall of the drawer, camming means pivotally arranged on each side wall of said body portion adjacent the side walls of the drawer, and means pivotally mounting said camming means as aforesaid and providing trunnions extending into the guiding channels for concerted action with said camming means to bind the follower in a desired position in the drawer.

4. In a follower for a filing drawer having guiding means, said follower comprising a base member disposed transversely of the drawer on the bottom wall thereof, means for wedging the base member in a desired position in the drawer, said means comprising lever means pivotally mounted on the end faces of said base member adjacent the side walls of the drawer, and trunnions pivotally mounting said lever means as aforesaid and projecting into the guiding means for sliding movement relative thereto, said lever means adapted to have bearing engagement with the bottom wall of the drawer to urge said trunnions into frictional engagement with one wall of the guiding means.

FRED C. DREBES.
